(73) Assignee: **Tencent Technology (Shenzhen) Company Limited** (CN)

(57) **CLAIM**

The ornamental design for a display screen portion with animated graphical user interface, as shown and described.

(**) Term: **14 Years**

DESCRIPTION

(21) Appl. No.: **29/476,370**

(22) Filed: **Dec. 12, 2013**

FIG. 1 is a front view of a first embodiment of a display screen portion with animated graphical user interface showing our new design;

FIG. 2 is a second image thereof;

(51) LOC (10) Cl. 14-04

FIG. 3 is a front view of a second embodiment of a display screen portion with animated graphical user interface showing our new design;

(52) U.S. Cl.

FIG. 4 is a second image thereof;

USPC **D14/487**

FIG. 5 is a front view of a third embodiment of a display screen portion with animated graphical user interface showing our new design; and,

(58) **Field of Classification Search**

FIG. 6 is a second image thereof.

USPC D14/485-495
CPC G06F 3/017; G06F 3/048; G06F 3/0481;
G06F 3/04842; G06F 3/04847; G06F 3/0485;
G06F 1/1692

In the first embodiment, the appearance of the transitional image sequentially transitions between the images shown in FIGS. 1 and 2. In the second embodiment, the appearance of the transitional image sequentially transitions between the images shown in FIGS. 3 and 4. In the third embodiment, the appearance of the transitional image sequentially transitions between the images shown in FIGS. 5 and 6. The process or period in which one image transitions to another image forms no part of the claimed design.

See application file for complete search history.

The broken lines shown in the figures of a display screen and portions of the graphical user interface, including the text, numbers and symbols are for the purpose of illustrating portions of the article, and form no part of the claimed design.
